UNITED STATES PATENT OFFICE.

SAMUEL A. SHORT, OF ALTOONA, PENNSYLVANIA.

RAIL-CLEANING DEVICE.

SPECIFICATION forming part of Letters Patent No. 611,290, dated September 27, 1898.

Application filed June 26, 1897. Serial No. 642,540. (No model.)

To all whom it may concern:

Be it known that I, SAMUEL A. SHORT, a citizen of the United States, residing at Altoona, in the county of Blair and State of Pennsylvania, have invented a certain new and useful Improvement in Rail-Cleaning Devices, of which the following is a full, clear, and exact description.

My invention relates to that class of devices usually employed in conjunction with a locomotive for the purpose of cleaning from the rails of the track the sand deposited thereon for the purpose of increasing traction of the drivers and to effect such cleansing before the wheels of the cars of the train come in contact with the sand.

My invention comprises an apparatus preferably arranged between the rear drivers of the locomotive and the front of the tender and connected with the steam-generator and with the water-tank and also with an air-pressure apparatus, such as the air-brake system, whereby steam, air, and water or any one or any two of these agents may be forcibly projected against the rails behind the rear drivers in order effectually to remove the sand that may have been deposited upon the rails, all as I will hereinafter more particularly set forth and finally claim.

In the accompanying drawings, illustrating my invention, in both figures of which like parts are similarly designated, Figure 1 is a transverse section, and Fig. 2 is a central cross-section.

In one form of my invention I employ a cylinder or reservoir *a*, which is suitably suspended or arranged between the rear driving-wheels of the engine and the front wheels of the tender and attached to the tender. This cylinder is connected by pipes *b* and *c* or in any other suitable manner with the water-tank, and the pipe *b* has a nipple *d*, which enters the cylinder. The pipe *b* also has a valve *e*, by which the admission of the water may be controlled. The heads of the cylinder *a* are provided with bosses *f*, from which extend pipes *g* to just above the rails of the track.

h is a strainer arranged transversely of the cylinder and communicating with the bosses *f*.

i is a pipe preferably having reduced ends arranged adjacent to the inlets to the pipes *g*,

and this pipe *i* is suspended by a pipe *j* from the boss or nipple *k*, into which is inserted a Y-pipe *l*, one of whose branches, as *m*, is connected with the steam-supply of the engine or boiler of a locomotive and the other, as *n*, is connected with any suitable air-pressure apparatus, and both of these pipes *m* and *n* may have suitable valves, as *m'* and *n'*, respectively, to open and close them.

Now when it is desired to remove sand from the rails water may be admitted to the cylinder through pipes *b c d* and allowed to overflow through the pipes *g* down to the rails and wash off the sand. If it be desired to apply the water with greater force, steam or air, either or both, may be admitted through the pipes *m* and *n*, whereby the water will be forcibly expelled. I prefer to use air and water in conjunction in cold weather instead of steam for the reason that the steam-vapors obstruct the view of the trainmen.

By the use of my invention an engine will haul two or three more loaded cars, because the removal of the sand reduces the traction of the car-wheels and thus reduces the duty of the engine, and, moreover, the wear of car-wheels and of rails is greatly reduced.

What I claim is—

1. A rail-cleaning device, comprising a reservoir, outlets therefor extending over the rails of the railroad-track, and means to supply water, steam and air or any combination thereof to the said outlets, substantially as described.

2. A rail-cleaning device, comprising a reservoir, a water-supply therefor, outlets leading from such reservoir to the rails, and steam and air inlets opening adjacent to said outlets, substantially as and for the purpose described.

3. A rail-cleaning device, comprising a reservoir having outlets leading to the rails; a water-supply, steam and air supplies, and means for controlling the supplies of water, steam and air, substantially as described.

Witness my hand this 31st day of May, A. D. 1897.

SAMUEL A. SHORT.
